UNITED STATES PATENT OFFICE.

CHARLES MADISON CROOK, OF CHICAGO, ILLINOIS, ASSIGNOR TO STROMBERG ELECTRIC COMPANY, OF CHICAGO, ILLINOIS, A CORPORATION OF MAINE.

TIME-RECORDER.

1,143,364.

Specification of Letters Patent. Patented June 15, 1915.

Application filed May 13, 1910. Serial No. 561,152.

To all whom it may concern:

Be it known that I, CHARLES MADISON CROOK, a citizen of the United States, residing at Chicago, in the county of Cook 5 and State of Illinois, have invented new and useful Improvements in Time-Recorders, of which the following is a full, clear, concise, and exact description, reference being had to the accompanying drawing, forming a 10 part of this specification.

My invention relates to improvements in time recorders and is particularly adapted for recording the time a workman begins and stops work.

15 It is particularly advantageous for use in shops, factories and the like, where it is desirable to record the time a workman passes into the works in the morning, out at lunch, in at the end of the lunch time, out again at 20 night and in and out time of extra working hours.

25 One of the advantageous features of my invention is that the impression mechanism is arranged to make an impression on the face of the time card when the card is inserted in the machine with its face toward the operator.

30 In practice, it is the usual custom to provide racks in proximity to the time recorder, in which racks each workman's card is supported face outward so that it can be readily seen. Heretofore time recording instruments for this class of work have been constructed so that the card must be inserted 35 in the recorder facing toward the rear of the machine or away from the workman. This necessitates the turning over of the card each time the workman inserts it in the machine for recording his time. While the 40 time consumed in thus turning over the card for each individual workman is slight, when it is multiplied by two or three hundred workmen, it becomes a seriously objectionable feature.

45 My recorder is so constructed that it overcomes the above objection.

It is one of the objects of my invention to provide an "in and out" time recorder which shall be strong and durable and which 50 will not readily get out of order under severe treatment.

Another object of my invention is to provide a recorder which may be operated in multiple, and which when so operated, all

of the recorders may be controlled from a 55 single clock mechanism whereby the danger of variance in time between the various recorders will be obviated.

For the purpose of disclosing my invention, I have illustrated in the accompanying 60 drawings and described in the specification one embodiment thereof.

In the drawings—Figure 1 is a front elevation of the recorder with the cover removed; Fig. 2 is a sectional view on the 65 line 2—2 of Fig. 1; Fig. 3 is a detail side elevation of the impression mechanism; Fig. 4 is a sectional view taken on the line 4—4 of Fig. 2; Fig. 5 is a sectional view taken on the line 5—5 of Fig. 1; Fig. 6 is a detail view of the card elevating mechanism; Fig. 7 is a sectional view taken on the line 7—7 of Fig. 4; Fig. 8 is a detail view of the means for laterally shifting the card holder; Fig. 9 is a sectional view taken on 75 the line 9—9 of Fig. 8; Fig. 10 is a sectional view taken on the line 10—10 of Fig. 4; Fig. 11 is a sectional view taken on the line 11—11 of Fig. 2; Fig. 12 is a perspective view of the setting key used in connection 80 with my recorder; Fig. 13 is a front elevation of the recorder; Fig. 14 is a face view of the card used in connection with the time recorder; Fig. 15 is a detail view of the in and out indicating mechanism; and Fig. 16 85 is a sectional view taken on the line 16—16 of Fig. 7.

In the embodiment of my invention illustrated in the accompanying drawings, I provide a time impression mechanism 17 which 90 preferably takes the form of the impression mechanism illustrated in my pending application Serial No. 466,486, filed December 8, 1908. It is not considered necessary in this present application to give a detail description of this impression mechanism. Suffice to say that the impression mechanism is provided with a plurality of impression wheels adapted to print the hours, minutes and the day of the week. Of course, other 95 indicia may be used in place of that above indicated, but I have found that in practical use these indicia are those which are generally preferred. Associated with this impression mechanism is an operating electromagnet 18 comprising a pair of solenoids, the armature 19 of which is connected to the impression mechanism and is adapted to ro- 100

tate the wheels of the impression mechanism in accordance with the change in time, the armature being preferably moved once every minute. Also associated with the impression mechanism is a hammer 20, operated from the exterior of the casing, by which the impression is caused to be made.

For holding the card in position with respect to the impression mechanism, I provide a card guide 21 which is laterally movable and associated with the card guide is means 22 for elevating the card in said guide to bring the day of the month indicated on the card in proper alinement with the impression mechanism.

The impression mechanism is mounted upon the upper end of an upwardly extending arm 23 secured to a pivoted frame 24, which frame is mounted upon a shaft 25 extending between a pair of horizontally extending supports 26 integrally formed with the base 27 of the instrument. The electromagnet 18 and the armature 19 operated thereby are also secured to this pivotally mounted frame 24.

Bolt extensions 28 of the cores of the solenoids are adapted to pass through openings in a pair of arms 29 formed on the frame and have nuts 30 secured on the rear end for holding the solenoids in position. Also secured on the frame 24 is an insulating base member 31 carrying connections 32 for the supply wires extending to the coils and also binding posts 33 to which the operating wires of the apparatus are adapted to be attached.

The hammer 20 for making the impression is mounted upon a shaft 34 extending between the two horizontal supporting members 26 and comprises a hammer arm 35 and a lever 36, which I preferably incline slightly forward. The lever 36 is arranged to coöperate with a cam wheel 37 mounted upon the shaft 25. Extending from the lever 36 is a short lever 38 to which one end of a coil spring 39 is attached, the opposite end of the spring being adapted to be attached to a post 40 extending outwardly from the base. This spring maintains the hammer in a forward position. When the cam wheel 37 is rotated by suitable operating mechanism the hammer is moved rearwardly and then released, and under the influence of the coil spring 39, snaps forward, striking the rear of the card and forcing the face thereof against the impression mechanism.

For the purpose of inking the impression mechanism, I provide an inking ribbon 41, and means in the form of a train of gears 42 suitably operated for moving the inking ribbon across the face of the impression mechanism to vary the point of contact of the ribbon with the impression mechanism from time to time.

For rotating the cam wheel 37, which is preferably provided with four cam surfaces, I provide a ratchet wheel 43 mounted on the hub of the cam wheel 37, and having the same number of cam surfaces as the cam wheel. This wheel 43 is partially rotated by a pawl 44 mounted on the outer end of a bell-crank lever 45 secured on a shaft 46 journaled in one of the horizontal side members 26 and adapted to extend through a slot 75 formed in the other side member to be supported in a journal 47 formed on the base. A second pawl 48 also mounted on the lever 45 is adapted to engage the ratchet wheel on its inner side to complete the movement 80 of the ratchet wheel.

For returning the lever 45 to normal position after each impression, I provide a coil spring 49, one end of which is connected to the armature supporting frame 24 and the other end to the second arm 50 of the bell-crank lever 45. The two pawls 44 and 48 are held into engagement with the ratchet wheel by a coil spring 51 which extends between them, serving to draw the ends of 90 the pawls together. The shaft 46 is operated by a suitable handle 52 which is detachably secured to the shaft 46. It will be noted that the front pawl 44 does not give a complete rotation of the cam 37 but 95 merely rotates the same far enough for the roller carried on the end of the lever 36 of the hammer to pass off the cam and snap inwardly. This much of the rotation given by the pawl 44 to the ratchet 100 wheel 43 is imparted as the handle 52 is turned downwardly, or on the downward movement of the pawl-carrying lever 45. The rest of the rotation of the ratchet 43 is given by the inner pawl 48 as the lever 105 returns to normal position. This peculiar movement is provided in order that there shall be no snapping action of the pawl 44 over the teeth of the ratchet wheel 43 which action would tend to wear out the teeth. 110

The ribbon feed mechanism 42 is driven from this same pawl-carrying lever 45. In practice, I provide a vertically extending lever 53, the upper end of which is pivoted to the frame of the impression mechanism 115 17. This lever is provided with a pawl 54 held into engagement with the ratchet wheel 55 of the ribbon-feeding mechanism by a coil spring 56, one end of which is connected to the pawl and the other end of which is 120 connected to the lever. The lower end of the lever 53 is provided with an inwardly inclined cam slot 57 adapted to fit over a roller 58 carried on the pawl-carrying lever 45, whereby as the lever 45 is carried downwardly the lower end of the lever 53 is moved outwardly, moving the pawl 54 up one tooth on the ratchet wheel 55 and as the pawl-carrying lever 45 moves upwardly again the lever 53 is moved inwardly, carry- 125 130

ing with it the pawl 54 which rotates the ribbon feed ratchet one step.

The card guide 21 comprises a skeleton frame-work having a pair of vertically extending guide members 59 connected at their upper ends with a flaring mouth piece 60 adapted to project through the top of the casing 61 so that the card may be readily inserted from the outside of the case. These two guide members 59 are connected at their lower ends by a bracing member 62 slotted to receive a guide pin 63 carried on one of the horizontal supporting members 26 of the impression mechanism. The card receiver is carried on a transversely extending rod 64 which is adapted to extend through openings, formed in inwardly extending projections 65 on the two side guides 59, and is supported at its outer ends upon a pair of upper horizontal supports 67, which at their inner ends are secured to the base 27.

The card guide is provided with a pair of inwardly extending arms 68 to which is secured a rack 69 adapted to mesh with a pinion 70 mounted on a stem 71 journaled in the base 27 and adapted to extend through the top of the casing.

Secured on the stem 71 is a thumb nut 72 which is arranged upon the exterior of the casing and is adapted to rotate the stem to move the guide 20 laterally. This thumb nut 72 is hollow and is secured upon the stem by a nut 73 adapted to screw on the outer end of the stem, a coil spring 74 being interposed between this nut and an annular shoulder 75 formed on the lower end of the thumb nut, to hold the thumb nut down. The bottom of the thumb nut is provided with grooves 76 adapted to engage an upwardly projecting pin 77 formed on the base. In order that the card guide may not be tampered with and may be only moved by persons in authority, the holding nut is provided with a small screw 78 having an annular shoulder 79 adapted, when the screw is set, to bear against an annular shoulder 80 formed on the interior of the thumb nut. By this arrangement, when the screw is set home, the thumb nut cannot be pulled upwardly and the grooves in the bottom thereof disengaged from the pin. The top of this screw 78 does not extend clear to the top of the thumb nut and is, at its end, provided with a key-receiving projection 81.

For preventing the screw from being removed entirely I provide an annular screw member 82 adapted to screw into the top of the thumb nut and provided with an opening into which the head of the small screw projects. By this arrangement it will be noted that when the key 83 is inserted and the small screw 78 turned until it is sufficiently raised to permit the thumb nut 72 to be raised to clear the stop 77, the thumb nut 65 can be rotated and the card guide moved lat-

erally. At the same time when the small screw 78 is seated, the thumb nut 72 cannot be raised and unauthorized persons cannot move the card guide 20 laterally, the key 83 being required for operating the screw 78.

As a slot must be left in the top of the casing to accommodate the lateral movement of the card guide 20, it is desirable to provide some means whereby this slot will be closed. This slot, in the present instance, is closed by a pair of arc-shaped follower members 84, one arranged on each side of the card guide 20 and adapted to follow the guide in its transverse movement. These arc-shaped followers are mounted upon arms 85 pivoted in turn upon the base 27 and are held into engagement with the sides of the guide 20 by a coil spring 86. By this arrangement the follower members do not take up a large amount of lateral space and securely close the unoccupied space of the opening in the casing.

For elevating the card so that the impression made thereon will correspond to the day of the week printed on the card, I provide a card elevator 22 which extends in the path of the card as it is placed in the card guide 20 and is carried by a transversely extending arm 87 supported on a vertically movable rack member 88. This rack member moves up and down on a vertical guide 89 carried on a horizontal arm 90 extending from the base 27. The front of the rack member is provided with a rack 91 adapted to mesh with the pinion 92 on an indicator wheel 93, the shaft of which is also carried by the horizontal arm 90. This wheel may have on its face any indicia desired, but in the present form has the days of the week. When the rack member 88 is in its lowermost position, Monday will appear on the front of the wheel. As the rack member is raised the succeeding days of the week will be caused to appear. The back of the rack member 88 is provided with a rack 94 adapted to mesh with a pinion 95 mounted upon a shaft 96 journaled in the arm 90. The pinion 95 has a blank portion 97 for a purpose more fully hereinafter described. A ratchet wheel 98 is mounted on the shaft 96 and is adapted to be engaged by the spring pressed pawl 99 for the purpose of holding the rack member 88 in any position to which it may be moved.

The shaft 96 is not of sufficient length to project beyond the side of the casing so that a key 83 must be used for rotating the same, a key projection 100 being provided on the end of the shaft for that purpose.

In operation, assuming the rack member 88 is in its lowermost position and therefore the card elevator is also in its lowermost position, the card may be inserted in the guide 20 and will drop down to the lowest point 180

whereby the impression will be made on the line indicated on the card as Monday. Turning the shaft 96 one notch will raise the card elevator so that the card will be printed on 5 the line indicating Tuesday, and the indicator wheel will be rotated to show Tuesday. The card elevator is made thus to rise until it reaches the limit of its upper movement at which time the blank portion 97 of the 10 pinion 95 will permit the rack member to drop by gravity rotating the indicator wheel and moving the elevator back to its Monday position. In rotating the shaft 96, there is danger of the operator, after the elevator is 15 moved to its uppermost position, and the rack has been permitted to drop by gravity, to rotate the shaft so rapidly that the teeth of the pinion 95 would again catch in the rack 94 before the same had dropped to its 20 lowermost position. This would throw the mechanism out of correct indicating position and would cause serious trouble before the same could be again adjusted. In order to prevent this, I provide a rotatable stop 101 25 at the end of the shaft 96 abutting the pinion 95 which will prevent the pinion from engaging the rack after the rack has reached its highest position until the rack has been returned to its initial position. This result 30 is accomplished by means of a plate 88^a secured to the inner face of the rack 88 and having a narrow upper portion 88^b exposing the teeth of the upper end of the rack and a wider portion 88^c covering the teeth on the 35 lower end of the rack. After the rack member has reached its highest position and the pinion passed out of engagement with the rack, if the pinion is turned in the direction of operative position before the rack has 40 dropped, the stop 101 will engage the end of the plate 88^a, as shown in Fig. 6, or if the pinion is turned quickly while the rack is falling, the stop 101 will strike against the outer face 88^c of the wide portion of the 45 plate and hold the pinion in that position until the rack has reached its lowermost position, as shown in Fig. 5, when the stop can pass off the side 88^d over the shoulder 88^e, thus permitting the pinion to again be 50 brought in engagement with the rack. Therefore, in order to let the rack drop back, this stop must be moved out of position.

Extending across the horizontal standard 67 is a cross member 103 upon which is 55 mounted a clock face 104, which is provided with hands adapted to be driven from the impression mechanism. The clock face is provided with an opening 105 and adapted to slide beneath the face is an "in and out" 60 indicator 106. I have shown in practice this indicator as having an A. M. in and A. M. out, P. M. in and P. M. out, and Extra in and out, whereby the various times of entering and leaving the establishment will be 65 indicated. This indicator moves in syn-

chronism with the card guide so that the proper position of the card may be readily ascertained. For moving the indicator 106 in synchronism with the card guide 20 it is connected therewith by a horizontal rod 107. 70 The base 27 which carries all of the above described mechanism is mounted on the back of the inclosing casing 61 the front portion 108 of which is removable and is provided with openings 109 and 110 through which 75 the clock dial and the indicating wheel may be observed. Every portion of the mechanism is completely inclosed by the casing with the exception of the thumb nut 72 for moving the card indicator laterally, and the 80 handle 52 for operating the impression hammer. The side of the casing is provided with an opening through which the key 83 may be inserted to operate the shaft 96 but it will be observed that this shaft does not project 85 beyond the face of the casing so that unauthorized tampering with the indicator wheel is prevented.

One of the side members 26 is provided with a bell 111 adapted to be struck by a 90 hammer 112 carried on the impression hammer shaft 34, whereby when the workman inserts his card and makes an impression the bell will ring.

While I have shown and described one 95 embodiment of my invention in the accompanying drawings and specification, it will be understood that various modifications and changes may be made herein without departing from the spirit of my invention as set 100 forth in the appended claims.

Having thus described my invention what I claim as new and desire to secure by Letters Patent, is—

1. In a time recorder, the combination with 105 a casing adapted to be secured against a wall, of a laterally movable card-holder arranged in said casing and having a portion thereof adapted to extend through said casing, and arc-shaped follower members arranged on each side of the said card-holder immediately beneath the opening in the casing, for closing that portion of the opening 110 not occupied by the card-holder.

2. In a time-recorder, the combination with 115 a casing, of a laterally movable card-holder arranged therein and adapted to have a portion thereof extend through said casing, arc-shaped closure members for closing that portion of the opening in the casing not occupied by the card-holder, and means for holding said followers in engagement with the card-holder, causing them to move synchronously with said card-holder.

3. In a time recorder, the combination with 125 a casing, of a card holder arranged in said casing, impression mechanism coöperating with said card holder also arranged in said casing, means for moving said card holder laterally, comprising a rotatable stem ar- 130

ranged exteriorly of the casing, a stop normally engaging said stem to prevent its rotation, said stem being vertically movable to permit it to be disengaged from said stop, 5 and key-controlled means for locking the stem against vertical movement.

4. In a time recorder, the combination with a casing, of a card holder arranged therein, time impression mechanism coöperating with 10 said card holder and also arranged within the casing, means for shifting the card holder laterally, a rotatable member arranged on the exterior of said casing for operating said means, a stop on said casing, 15 a shoulder on said rotatable member, said rotatable member being vertically shiftable to be disengaged from said stop, and key-controlled means for locking the rotatable member against vertical movement.

20 5. In a time recorder, the combination with impression mechanism, of a hammer associated with said impression mechanism and means for operating said hammer, comprising a rotatable cam, a ratchet wheel connected with said cam and adapted to be rotated a definite distance to cause the cams to operate the hammer, a pawl for rotating said ratchet wheel a part of the said distance and a second pawl for rotating the 25 pawl the balance of the distance.

6. In a time recorder, the combination with impression mechanism, of a hammer associated with said impression mechanism, means for operating said hammer comprising 30 a cam wheel, a ratchet wheel for rotating said cam wheel, and a pair of pawls for rotating said ratchet wheel arranged on opposite sides of said ratchet wheel.

7. In a time recorder, the combination with 40 impression mechanism, a hammer associated with said impression mechanism, means for operating said hammer comprising a cam wheel, a ratchet wheel for rotating said cam wheel, a lever, a pawl carried by said lever and arranged upon one side of said ratchet wheel and a second pawl carried by said lever and arranged upon the opposite side of said cam wheel, one of said pawls being arranged to rotate the cam wheel as the 45 lever is moved in one direction, the other pawl being arranged to rotate the cam wheel as the lever is moved in the opposite direction.

8. In a time recorder, the combination with 50 a card-holder, of card-elevating mechanism associated therewith comprising a card elevator, a rack connected therewith, a rack wheel adapted to mesh with said rack to raise the same and having a portion thereof blank, whereby when the rack has been 55 raised to a sufficient extent the wheel will be disengaged therefrom, and means for preventing the rack wheel from again engaging the rack until the rack has been moved back 60 to normal position.

9. In a time recorder, the combination with a card-holder, of card-elevating mechanism associated therewith comprising a card elevator, a rack connected therewith, a rack wheel for operating the same, having a blank 70 portion thereon whereby the wheel will become disengaged from the rack after it has been moved a predetermined distance, a ratchet wheel connected with said rack wheel, and a pawl adapted to engage the 75 teeth of said ratchet for holding the rack in any position to which it may be moved.

10. In a time recorder, the combination with a card-holder, of a card-elevating mechanism associated therewith comprising a card elevator, a rack connected therewith, a stop portion arranged at the bottom of said rack, a rack wheel adapted to engage said rack to move the same and having a portion thereof blank, whereby the wheel will be disengaged from the rack after it has been moved to a predetermined position, and a stop carried with said rack wheel adapted to engage said stop portion on the 80 rack to prevent the teeth of the wheel from 85 being moved into engagement with the rack until the rack has been moved to normal position.

11. In a time recorder, the combination with a card holder, of impression mechanism associated therewith, a platen coöperating with said impression mechanism, means for causing a relative movement between said platen and impression mechanism, comprising a rotatable cam and 90 ratchet for operating said cam, an arm, 95 pawls mounted on said arm for rotating said ratchet, a ribbon for inking said impression mechanism, feed mechanism for said ribbon, and means connected with said 100 arm for operating said ribbon feed mechanism.

12. In a time recorder, the combination with a card holder, of impression mechanism associated therewith, a platen coöperating with said impression mechanism, means for causing a relative movement between said platen and impression mechanism, comprising a rotatable cam, a ratchet for operating said cam, an arm, pawls arranged on said arm for rotating said ratchet, 110 a ribbon for inking said impression mechanism, feed mechanism for said ribbon, a lever connected with said arm, and pawl and ratchet mechanism operated by said 115 lever for operating the ribbon feed mechanism.

13. In a time recorder, the combination with an impression mechanism, of a laterally movable card-holder in front of and 120 associated with said impression mechanism, a clock associated with said impression mechanism and driven thereby, an opening in the face of said clock, and an indicator 125 arranged to move synchronously with said 130

- 6
- card-holder arranged behind said clock dial and adapted to be read through said opening.
14. In a time recorder, in combination, a rear supporting base, a platen mounted in front of said base, a self-contained unitary impression mechanism comprising hour and minute revoluble printing wheels mounted in a horizontally straight line in front of said platen, a card receiver mounted between said platen and impression mechanism, arranged to permit insertion and withdrawal therefrom of an impression receiving card, and laterally movable to cause the impression mechanism to print in vertical columns, said impression mechanism being mounted in front of the card holder to make an impression on the card when the same is inserted in the holder with its face toward the operator, an electromagnet suitably mounted and arranged to be intermittently energized, the armature of which operates a lever mechanism for intermittently rotating the type wheels of the printing mechanism, and a vertically movable step on which the bottom of the card rests, constructed to be raised step by step to cause the impression mechanism to make impressions on different horizontal lines.
15. A time recorder of the type making straight line impressions, having in combination a rear supporting base, a vertically arranged card receiver mounted in front of said base and laterally movable to cause impressions to be made in different vertical columns on the impression receiving card, a platen extending between said base and card receiver, an impression mechanism comprising revoluble type wheels mounted in a horizontally straight line, said impression mechanism being mounted in front of the type holder and constructed and arranged to make the impression on the front of the impression receiving card when said card is inserted in the holder with its front toward the operator, a suitably mounted electromagnet arranged to be intermittently energized, the armature of which is mechanically connected with the impression mechanism to intermittently operate the type wheels thereof, said platen and impression mechanism having a relative movement to permit the making of an impression.
16. In a time recorder, in combination, a casing, impression mechanism arranged in said casing, a card holder for supporting a card within said casing while receiving an impression and laterally shiftable to permit the impression to be made at various points on the card, said casing having a slot in the top thereof to accommodate the card holder and of sufficient length to permit the holder to travel to the limit of its lateral movement, and closure members on either side of said card holder immediately beneath the slot for closing that portion of the slot unoccupied by the card holder, and arranged to move, as the card holder is laterally shifted, in a path extending beneath the top of the casing and along the sides of the casing.
17. In a time recorder, in combination, a casing, impression mechanism in said casing, a card holder for supporting a card within said casing while receiving the impression and laterally movable to permit the impression to be made in different vertical columns on the card, said casing having a slot in the top thereof to accommodate the card holder and of sufficient length to permit the card holder to travel to the limit of its lateral movement, and closure members arranged on either side of said card holder immediately beneath the slot for closing that portion of the slot unoccupied by the card holder, said closure members being held against the card holder by spring pressure to cause the same to move with the card holder.
18. In a time recorder, in combination, a casing, impression mechanism in said casing, a card holder for supporting a card within said casing while receiving the impression to permit the impression to be made in different vertical columns, a slot in the top of the casing to accommodate the card holder and of sufficient length to permit the holder to travel to the limit of its lateral movement, follower members independently supported with respect to the card holder on either side of said card holder and immediately beneath the slot for closing that portion of the slot unoccupied by the card holder, and means for causing said follower members to automatically move with the card holder.
19. In a time recorder, in combination, a casing, impression mechanism arranged within said casing, a card holder for supporting a card in position to receive an impression from said mechanism and laterally movable to permit the impression to be made in different vertical columns, shifting mechanism for said card holder for moving the same laterally within said casing, a rotatable stem extending through said casing for operating said shifting mechanism, stops on said casing arranged to engage the lower portion of said stem to prevent the rotation thereof, said stem being vertically movable for disengagement from said stops, and key-operated mechanism for locking said stem against vertical movement.
20. In a time recorder, in combination, a casing, impression mechanism mounted in said casing, a card holder for supporting the card within said casing in a position to receive an impression from said mechanism and laterally movable to permit an impression to be made at various points on the card, shifting mechanism within the

- casing for moving said card holder laterally to permit the impression to be made in different vertical columns, a rotatable thumb nut on the exterior of said casing 5 connected with said shifting mechanism, a stop on said casing normally engaging said thumb nut, said thumb nut being vertically movable to be disconnected from said stop, means for locking said thumb nut against 10 vertical movement, and a separable key for operating said locking means.
21. In a time recorder, in combination, a casing, impression mechanism within said casing, a card holder for supporting a card 15 in position to receive an impression from said mechanism and laterally shiftable to permit the impression to be made in different vertical columns, shifting mechanism for said card holder, comprising a rack connected therewith, and a pinion rotatably mounted on a shaft extending through the top of said casing, a thumb nut vertically movable on said shaft, a stop on said casing engaged by said thumb nut for preventing 20 the same from operating, and key-operated means for locking the said thumb nut against vertical movement.
22. In a time recorder, in combination, a casing, impression mechanism mounted 25 within said casing comprising a base member secured to the back of said casing, an arm pivotally mounted on said base member, a self-contained time impression mechanism mounted on said arm, and a card holder arranged between said base and said impression mechanism and a platen mounted on 30 said base.
23. In a time recorder, in combination, a casing, impression mechanism arranged 35 within said casing comprising a base member secured to the back of said casing, an arm pivoted at its lower end to said base member, a self-contained time impression mechanism mounted on the upper end of 40 said arm and comprising a plurality of revoluble type wheels arranged in a horizontally straight line operated in train, an electromagnet mounted within said casing and mechanically connected with said type 45 wheels for operating the same, a laterally shiftable card holder arranged within said casing and extending between said type wheels and the back of the casing, and a platen arranged in the rear of said card holder. 55
24. In a time recorder, the combination with a casing, of a base secured to the back of said casing, an arm pivoted to said base, a head mounted on the top of said arm and carrying revoluble type wheels operated in 60 train and arranged to print in a straight line, means for rigidly securing said head against movement, a dial having movable indicating members operating synchronously with said printing wheels and view- 65 able from the exterior of the casing, a card holder arranged within said casing and mounted behind said head, said card holder being laterally movable to permit an impression to be made thereon in different vertical columns, and a platen mounted between the back of said casing and the card holder. 70
25. In a time recorder, the combination with a casing, of a base secured to the rear 75 of said casing, an arm pivotally mounted on said base, a head secured to the upper end of said arm and carrying revoluble type wheels operating in train, an electromagnet mounted on said arm and mechanically connected 80 with said type wheels for intermittently operating the same, a laterally shiftable card holder mounted between said arm and said base, a card elevator arranged within said casing for moving the card vertically, a 85 movable platen mounted between the back of the casing and said card holder, means arranged upon the exterior of said casing for operating said platen to cause an impression to be made, and key-operated means 90 for operating said card elevating mechanism. 90

In witness whereof, I have hereunto subscribed my name in the presence of two witnesses.

CHARLES MADISON CROOK.

Witnesses:

E. R. KING,
W. PERRY HALEY.

Corrections in Letters Patent No 1,143,364.

It is hereby certified that in Letters Patent No. 1,143,364, granted June 15, 1915, upon the application of Charles Madison Crook, of Chicago, Illinois, for an improvement in "Time-Recorders," errors appear in the printed specification requiring correction as follows: Page 4, strike out the sentence contained in lines 51-52; same page, lines 106-107, strike out the words "adapted to be secured against a wall"; page 6, line 12, for the word "withdrawl" read *withdrawal*; same page, line 25, for the word "stap" read *stop*; and that the said Letters Patent should be read with these corrections therein that the same may conform to the record of the case in the Patent Office.

Signed and sealed this 27th day of July, A. D., 1915.

[SEAL.]

R. F. WHITEHEAD,

Acting Commissioner of Patents.
